UNITED STATES PATENT OFFICE.

JOHN A. MACDOWELL, OF ST. LOUIS, MISSOURI.

TOOL FOR PLACING CLEARANCE WRAPPERS ON BOILER TUBES.

Application filed December 31, 1925. Serial No. 78,630.

This invention relates to a specially constructed spring-set clearance or space wrapper for the water tubes of steam boilers, and to a tool for facilitating the placing of such wrappers upon the said tubes of steam boilers, preparatory to the construction or repair of the baffles thereof.

In the building of the usual concrete or like baffle plates in steam boilers, it is the common practice to leave clearance spaces between the boiler tubes and the baffle wall, which spaces are calked with paper wrappers or the like which contribute to the easy removal of old tubes and their like easy replacement by new ones.

This structural feature further eliminates the transmission of vibration from the tubes to the baffle wall during the process of tур-
bining, and there are other advantages at-
taching to this structural feature. In order
20 to ensure such clearance spaces in the build-
in of baffle walls, wrappers of thick paper
are commonly placed around the boiler
tubes in the plane of the proposed wall,
25 spaced wall forms are then mounted in po-
sition, and the viscous concrete or other
material is poured in between the forms.
This material readily flows into place be-
tween the forms and around the tubes cov-
30 ered as stated by the said wrappers, and
when the material is hardened and the
forms are removed, the wall is left com-
plete with the spacing wrappers locked in
place.

35 The object of the present invention is to provide a simple, practical and efficient resilient or spring-set clearance or space wrapper, adapted normally to assume a circular form so as automatically to encircle the water tube, and a tool to facilitate the placing of such space or clearance wrappers upon the tubes in the construction or repair of the described baffle walls.

45 In the drawing Figure 1 is a side elevation of the tool as in use, showing a clearance wrapper stretched thereupon in process of application to a boiler tube;

Figure 2 is a view of a section of an old baffle wall in process of repair, and showing a clearance wrapper as applied thereto by the use of this tool;

55 Figure 3 is an enlarged detail of the working end of the tool, showing the wrapper securing latches;

Figure 4 is an enlarged detail of one of the wrappers;

Figure 5 is a detail showing a modified means for releasably fastening the forward end of the spring ring to the handle bar; co

Figure 6 shows a wrapper as integrally formed of resilient material and adapted to normally assume the form of a parted cylinder.

The invention comprises a suitable handle bar 1, which is preferably flat and is provided at the forward or working end with a bracket or lug 2 from which protrudes a fastening pin 3 disposed across and parallel to the face of the handle. A flat latch bar 4 is slidably mounted through loops 5 in connection with the handle bar 1, the said loops being secured to the said handle bar. The forward or working end of the latch bar 4 is provided with a latch 6 in the nature of a lip which is spaced from the bar 1 and lies parallel thereto. A clearance wrapper 7 is provided, the same being made of heavy paper or other suitable flexible material, and a spring loop or parted ring 8 is incorporated therein. This is accomplished in a simple and effective manner by encircling the wrapper with the ring and passing the ends 9 of the ring through slits 10 cut in the wrapper. The ring is so mounted in connection with the wrapper as to cause the latter to curl in the form and manner in which it is intended to embrace or encircle the boiler tube 11 when placed in position thereupon, and the ends of the ring 8 approximately coincide with the ends of the wrapper 7, although this detail is immaterial. One end of the ring 8 is curled into the form of an eyelet 12.

In use and operation the wrapper 7 is 95 extended upon the end of the bar 1 by hooking the eyelet 12 upon the pin 3 and then uncoiling the rig and wrapper and sliding the latch 6 up over the opposite end of the extended ring, as shown in Figure 1. The 100 wrapper thus stretched upon the tool is properly positioned against that part of the boiler tube 11 where it is desired to impose the wrapper, as shown in Figure 1. The latch bar 4 is then drawn backward relative to the bar 1, the latch 6 is withdrawn from the end of the ring 8, and immediately that end of the ring flies loose and encircles the tube 11. The handle bar 1 is then so manipulated as to withdraw the pin 3 from 105 110

the eyelet 12, thus leaving the wrapper 7 properly mounted in place upon the tube 11.

Various modifications of the method of releasably mounting the spring-set wrapper upon the tool might be adopted. For instance, as shown in Figure 5, instead of the lug 2 and pin 3, an auxiliary latch 13 may be mounted at the forward end of the bar 1, the same being a duplicate of the latch 6 and arranged in direct alignment therewith. The ring 8 would then be left uniform throughout and at both ends, the eyelet 12 being omitted and the ends of the ring 8 being simply extended and pressed down under the latches 6 and 13. Furthermore, if the wrapper 7 were made of somewhat resilient material and formed and set cylindrically, as shown in Figure 6, the spring ring 8 might be dispensed with, as the wrapper would of itself form its own resiliency coil around the tube 11 when released from the latches 6 and 13.

While I have herein described a certain specific manner and method of constructing and assembling the elements of my invention, it is understood that I may vary from the same in minor details, not departing from the spirit of my invention, so as best to construct a practical device for the purpose intended, as defined in the appended claim.

I claim:

In a device of the kind described, a handle bar having a working end; a fastening pin at the working end of the handle bar; a latch bar slidably mounted in connection with the handle bar, the said latch bar having a working end disposed adjacent the working end of the handle bar; and a latch at the working end of the latch bar disposed in alignment with the said fastening pin at the working end of the handle bar.

In testimony whereof I affix my signature.
JOHN A. MACDOWELL.
